UNITED STATES PATENT OFFICE.

WILLIAM R. POTTER, OF BUCKHOLTS, TEXAS.

BALING-PRESS.

1,075,494.

Specification of Letters Patent. Patented Oct. 14, 1913.

Application filed April 21, 1913. Serial No. 762,517.

To all whom it may concern:

Be it known that I, WILLIAM R. POTTER, a citizen of the United States, residing at Buckholts, in the county of Milam and 5 State of Texas, have invented certain new and useful Improvements in Baling-Presses, of which the following is a specification.

This invention as specified relates to new and useful improvements in baling presses. 10 The object of the invention is to provide a press of the double bale type comprising certain novel features of construction including elevators, a reciprocating press head, and mechanism of a particular form 15 for reciprocating the head and operating the elevators.

A still further object of the invention is to provide a device of the character described that will be strong, durable, efficient 20 and simple and comparatively inexpensive to construct, also one in which the several parts will not be likely to get out of working order.

With the above and other objects in view 25 the invention has relation to certain novel features of construction and operation, an example of which is described in the following specification and illustrated in the accompanying drawings, wherein:

30 Figure 1 is a side elevation of the press, Fig. 2 is a plan view, Fig. 3 is a transverse vertical sectional view on the line $x-x$ of Fig. 1, and Fig. 4 is a transverse vertical sectional view on the line $y-y$ of 35 Fig. 1.

In the drawings the numeral 1 designates a frame comprising a central press box 2 and opposed baling chambers 3 on each side of the press box, the latter being of 40 the usual construction. In the sides of the press box opposed longitudinal slots 4 are arranged to receive horizontal pins 5 projecting from a press head 6 extending transversely of the press box and having a snug 45 sliding fit therein. A carrier 7 disposed under the bed of the press box has vertical standards 8 on each side of the press box and to which the pins 5 are secured. By reciprocating the carrier the press-head 50 alternately presses material into the opposed baling chambers 3.

The upper side of the press box is open and at opposite sides elevators discharge 55 into the press box. Each elevator comprises a suitable frame 9 inclined as shown and secured at its upper end to the sides of

a hopper 10 mounted on the press box. An endless chain 11 is suitably mounted in each frame and driven by a shaft 12 at the upper end. At one side of the press a shaft 14 60 extends at an angle from bottom to top thereof. This shaft is driven at its lower end by means hereinafter described. A bevel gear 15 is fixed on the upper end of the shaft and meshes with a bevel pinion 65 16 fixed on the end of a transverse counter shaft 17 suitably supported at one end of the hopper. A similar pinion 18 is fixed on the opposite end of the counter shaft. The pinions 16 and 18 mesh with bevel pinions 70 19 fixed on the adjacent ends of the shafts 12 and in this way motion is imparted to the elevators. Straw or other material to be baled deposited on the elevators will be conveyed to the hopper 10 and discharged 75 thereinto.

The carrier 7 is mounted on a central reciprocating link 20 mounted in a channel shaped member 26 disposed between hangers 21 suspended from the under side of 80 the press frame. This member 26 supports a plurality of spaced transverse rollers 22 on which the link is adapted to reciprocate. The carrier 7 has a plurality of spaced transverse rollers 23 which bear against angle 85 irons 24 secured to bottom of the press frame as best shown in Fig. 3. The rollers 22 take the downward thrust of the link and carrier and the rollers 23 take the upward thrust. The hangers are attached to the 90 press frame at points beyond the ends of the stroke of the press head as shown in Fig. 1. Angular guides 25 are secured to the hangers so that the carrier will slide over the same and will be prevented from 95 tilting down at either side.

At one end of the press frame a pair of hangers 27 similar to hangers 21 support the extremity of the member 26. On the end of the link opposite to the carrier, a rack-loop 28 is provided. This rack-loop has an oblong internal gear rack 29. The upper side of the loop bears against transverse rollers 30 mounted between angle irons 31 secured to the bed of the press frame as is 100 best shown in Fig. 4. For reciprocating the link, a pinion 32 is disposed in the rack-loop 28 so as to engage the gear rack 29 and when rotated alternately meshes with the upper and lower rows of teeth, being carried 105 from one row to the other by the curved ends of the rack 29. A guide bar 33 sup-

ported on the rack-loop terminates short of the ends of the internal gear. The pinion 32 is fixed on a shaft 34 which carries on its free end a roller 35. The roller 35 bears on 5 the bar 33 when the pinion 32 meshes with the upper row of teeth thus holding the pinion in place. This form of gearing is well known and a detailed description is not believed necessary.

10 The shaft 34 has connection with a counter shaft 36 by means of a universal joint 37, a yoke hanger 38 is suspended from the bed of the press frame and provides a bearing for the shaft 36 and a guide for the shaft 34 15 which plays up and down in a slot 39 in said hanger. A bearing bracket 40 extends outward from the yoke hanger and also supports the shaft 36 which carries a gear 42 on its outer end. The gear 42 meshes with a 20 gear 43 mounted on a shaft 44 supported in a bracket 45 projecting from the side of the press frame over the shaft 36. A driving pulley 46 is fixed on the outer end of the shaft 44 to which motion may be imparted 25 in any desired manner.

Motion imparted to the pulley 46 is transmitted to the link 20 by the gears 43 and 42 shaft 36, shaft 34, pinion 32 and rack 29. The link is thus reciprocated as is likewise 30 the press-head 6 which is supported by the carrier 6 which is secured on the link. Material discharged into the press box 2 by the elevators and falling into the path of the press head will be pressed into the baling 35 chambers 3, said chambers being charged alternately. For transmitting motion to the elevators the shaft 14 carries a bevel gear 47 on its lower end which is driven by a like gear 41 fixed on the shaft 36.

40 What I claim is:

1. The combination in a baling press, of a press frame having a press box arranged between opposed baling chambers, a press head working in the press box, a carrier 45 mounted to reciprocate under the frame and having positive connection with the press head through the side of the press frame, transverse rollers carried by the carrier and bearing against the underside of the press 50 frame, hangers suspended from the press frame, a channel member supporting the lower ends of the hangers, a link having re-

ciprocating movement between the hangers and confined thereby against lateral displacement, the carrier being fixed on one end of the link, transverse rollers journaled in the channel member and supporting the link, angular guide bars mounted on the hangers at their outer sides and receiving the carrier, an operating head mounted on the link, supports mounted on the underside of the press frame and receiving the link head therebetween, rollers journaled between the supports and against which the head bears, and means for imparting a reciprocatory motion to the link head.

2. The combination in a baling press, of a press frame having a press box arranged between opposed baling chambers, a press head working in the press box, a carrier 70 mounted to reciprocate under the frame and having positive connection with the press head through the sides of the press frame, transverse rollers carried by the carrier and bearing against the underside of the press 75 frame, hangers suspended from the press frame, a channel member supporting the lower ends of the hangers, a link having reciprocating movement between the hangers and confined thereby against lateral displacement, the carrier being fixed on one end of the link, transverse rollers journaled in the channel member and supporting the link, angular guide bars mounted on the 80 hangers at their outer sides and receiving the carrier, an operating head mounted on the link, supports mounted on the underside of the press frame and receiving the link head therebetween, rollers journaled between the supports and against which the 85 head bears, means for imparting a reciprocatory motion to the link head, a gearing connected with the link head, a support for said gearing mounted on the press frame, and means for transmitting motion to said 90 gearing.

In testimony whereof I have signed my name to this specification in the presence of two subscribing witnesses.

WILLIAM R. POTTER.
